UNITED STATES PATENT OFFICE.

LOUIS E. ARMSTRONG, OF FORT DODGE, IOWA.

VITRIFIED BLOCK.

1,163,880.

Specification of Letters Patent. Patented Dec. 14, 1915.

Application filed December 12, 1914. Serial No. 876,775.

To all whom it may concern:

Be it known that I, LOUIS E. ARMSTRONG, a citizen of the United States, residing at Fort Dodge, in the county of Webster and State of Iowa, have invented certain new and useful Improvements in Vitrified Blocks, of which the following is a specification.

My invention relates to vitrified blocks 10 designed primarily for constructing sewers.

Blocks designed for sewer construction or similar purposes and which are placed beneath the ground must be capable of resisting considerable pressure. In the making 15 of vitrified blocks where strength as well as lightness are both necessary requisites, it has always been necessary to keep within certain well defined limits, as to thickness of the walls of the block, or partitions there- 20 of, on account of the difficulties in firing and drying thick sections of the clay or other material from which such blocks are ordinarily constructed.

The principal object of my invention, 25 therefore, is to construct a vitrified block that is capable of withstanding considerable pressure from all directions and yet having walls of such a thickness that they may be readily fired and dried, and thus 30 producing a strong and light structure.

A further object of my invention is to improve the end joint seals between adjacent blocks whereby the joint ends are held in more rigid and permanent contact than 35 heretofore.

In the accompanying drawing—Figure 1 is an end view of a sewer or conduit formed of my improved blocks; a portion thereof being shown in section. Fig. 2 is an end 40 view of my improved block. Fig. 3 is a longitudinal sectional view of one of my improved blocks and the meeting ends of adjacent blocks. Fig. 4 is a perspective view of my improved blocks.

Referring now more particularly to the drawing, my invention consists of a block 45 having a top wall 5, a bottom wall 6, end walls 7 and 8 and truss walls 9 and 10 inter- posed between the top and bottom walls 5 and 6 respectively. The walls 9 and 10 di-

verge from the top wall 5 so as to form a truss within the block.

Each block is made with a rib 11 extending along one side wall and a groove 12 along the other side wall, adapted for interlocking engagement with the rib 11 of an adjacent block. The top and bottom walls are arched, while the end walls converge toward the bottom wall. The block is so formed that at one end the lower wall 6 extends beyond the upper wall 5, while at the other end of the block, the lower wall is cut away, as shown at 13, whereby a ship-lap joint is obtained at the meeting ends of adjacent blocks.

It is desirable to seal the ship-lap joints with mortar, and to obtain a clench between the mortar and the meeting ends of adjacent blocks, I form flanges 14 upon the inner faces of the side walls 11 and 12 which project toward the trusses 9 and 10 but leave a sufficient space between the ends of the flanges and trusses in order that mortar may pass therebetween. Similar flanges 15 are formed upon the trusses 9 and 10 which project inwardly but do not meet. The flanges 14 and 15 are disposed slightly above the bottom wall of the block and serve as surfaces around which the mortar may form a clench and thereby mechanically lock the 75 meeting ends of adjacent blocks together.

Having now described my invention I claim:

1. A vitrified block comprising top, bottom and side walls, flanges formed integral with said side walls adjacent the bottom wall and projecting inwardly toward each other but not connected, whereby a mortar receiving recess is formed between said flanges and bottom wall.

2. A vitrified block comprising top, bottom and side walls, flanges formed integral with said side walls and arranged in substantially the same plane above said bottom wall, said flanges extending toward each other for a relatively long distance and unsupported at their outer ends.

3. A vitrified block comprising top, bottom and side walls, a flange upon each side wall extending inwardly therefrom and ar- 100

ranged substantially parallel to said bottom wall, said flanges being less in thickness than said side walls and unsupported at their outer ends.

5 4. A vitrified block comprising top, bottom and side walls, converging truss walls between said top and bottom walls and flanges upon said end and truss walls arranged

above said bottom wall, said flanges being unsupported at their outer ends and arranged substantially parallel to said bottom wall.

LOUIS E. ARMSTRONG.
